UNITED STATES PATENT OFFICE.

FRANK RUDOLPHI, OF MONTCLAIR, NEW JERSEY, ASSIGNOR TO AMERICAN CAN COMPANY, OF NEW YORK, N. Y., A CORPORATION OF NEW JERSEY.

CONVEYER FOR SHEETS OF MATERIALS.

1,104,548.

Specification of Letters Patent. Patented July 21, 1914.

Application filed March 9, 1912. Serial No. 682,589.

To all whom it may concern:

Be it known that I, FRANK RUDOLPHI, a citizen of the United States, residing in Montclair, in the county of Essex and State 5 of New Jersey, have invented a new and useful Improvement in Conveyers for Sheets of Materials, of which the following is a specification.

This invention relates to improvements in 10 conveyers such as are used in "dry kilns" for drying lacquered and decorated plates used in the manufacture of can bodies and similar articles.

The object of this invention is to provide 15 such a conveyer that will be cheap to manufacture, simple in design, and one that will not scratch or mar the plates when the same are placed on the conveyer, and one wherein the plates may be guided easily and rapidly 20 into position by the operator.

In conveyers of this type as formerly constructed, the carrying member has been provided with a plurality of spaced, vertically extending rods, and it has been the custom 25 of the operator to place a sheet between the corresponding pairs of these rods. In practice, however, it has developed with this construction that the tops of the rods often mar the lacquered and decorated plates, and 30 furthermore, that it requires considerable skill for the operator to place the sheets of material in the proper pairs of rods, and also while the plates are being conveyed through the drying kiln, the plates having 35 no support except at each end, sag in the middle and thus are likely to contact each other.

One construction which I have shown in the drawings, and as hereinafter described, 40 embodying my invention, consists in a conveyer comprised of two spaced, parallelly arranged link chains, preferably provided with anti-friction rollers and adapted to run over guides or a table, and a plurality 45 of equally spaced rods on each pair of links, said rods being in the form of an inverted U shape.

My invention furthermore consists in the improvements in the parts and devices and 50 in the novel combinations of parts and devices herein shown and described or claimed.

In the drawing forming a part of this specification, Figure 1 is a side elevation of 55 a portion of a conveyer embodying my im-

provements, showing in dotted lines the position assumed by the sheets when placed on the conveyer. Fig. 2 is a vertical section, taken on the line 2—2 of Fig. 1, and showing in dotted lines one of the sheets 60 of material in place, and Fig. 3 is a horizontal sectional view of a portion of the conveyer, taken on the line 3—3 of Fig. 1.

In the drawings, 10 denotes the conveyer, comprising a pair of spaced, parallelly arranged link chains 11, each of said chains being preferably provided with anti-friction rollers 12 secured to the pivots between adjacent links and adapted to run on guide- 65 ways 13. The links of the chains 11 are arranged in pairs, and extending across from one link to the other are a plurality of equally spaced members or rods 14 secured at their ends in the links, said rods or members 14 being in the form of an inverted 70 U shape, having a slightly upwardly tapered portion 15 at their center.

In operation, the sheets 16 are placed by the operator one between each pair of members 14, and owing to the rod being continuous 80 from one chain to the other, it becomes impossible for the operator to misplace the sheets, and due to the upwardly extending central portion 15 of each member 14, the sheets are easily slipped into place, and furthermore, the horizontally extending portion of the inverted U-shaped member forms a support for the central portion of the sheet as the same is being conveyed through the drying kiln and thus prevents sagging 85 of the sheet. Furthermore, it will be obvious there are no sharp points or ends to come into contact with the lacquered and decorated sheets or plates while the same are being slipped into position by the operator. 90

The structure which I have shown embodies one form of my invention, but it will be apparent that many changes and modifications may be made in the same 100 without departing from the spirit of the invention, and all such changes and modifications are contemplated as fall within the scope of the appended claim.

I claim:

A conveyer adapted to carry sheets of material comprising, in combination, a chain having spaced, parallelly arranged links arranged in pairs, supporting means for said chain, and a plurality of members extend- 110

105

ing between each pair of links, each of said members comprising an inverted, substantially U shaped member whereby a plurality of sheets are adapted to be supported by each pair of links of the chain and retained by said members separated from each other, the horizontal portion of the U shaped members serving to form a support for the middle portions of the sheets.

FRANK RUDOLPHI.
